DESIGN FOR A SLIP

Arthur Imerman, New York, N. Y., assignor to
La Paree Undergarment Co., Inc., Jersey City,
N. J., a corporation of New Jersey

Application July 14, 1938, Serial No. 78,465

Term of patent 7 years

To all whom it may concern:

Be it known that I, Arthur Imerman, a citizen of the United States, residing in New York city, in the county and State of New York, have invented a new, original, and ornamental Design for a Slip, of which the following is a specification; reference being had to the accompanying drawing, forming part thereof.

Fig. 1 is a front view of a slip, showing my new design.

Fig. 2 is a side view thereof.

The back view of the garment is substantially similar to the front view.

I claim:

The ornamental design for a slip, substantially as shown and described.

ARTHUR IMERMAN.
